US0D1110495S

(12) **United States Design Patent** (10) **Patent No.:** **US D1,110,495 S**
(45) **Date of Patent:** **** Jan. 27, 2026**

(54) **A/C UNIT VENT HOSE CONNECTOR**

(71) Applicant: **Nanhua Yu**, Guangdong (CN)

(72) Inventor: **Nanhua Yu**, Guangdong (CN)

(**) Term: **15 Years**

(21) Appl. No.: **29/984,857**

(22) Filed: **Jan. 15, 2025**

(51) **LOC (15) Cl.** **23-03**

(52) **U.S. Cl.**

USPC **D23/393**

(58) **Field of Classification Search**

USPC D23/328, 333, 341, 354, 386-387,
D23/390-393

CPC F24F 7/013; F24F 7/007; F24F 7/00; F24F
2007/001; F24F 13/02

(57) **CLAIM**

The ornamental design for an A/C unit vent hose connector as shown and described.

DESCRIPTION

FIG. 1 is a perspective view of an A/C unit vent hose connector showing my new design;

FIG. 2 is another perspective view thereof;

FIG. 3 is another perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof; and,

FIG. 9 is a bottom plan view thereof.
